UNITED STATES PATENT OFFICE.

DAVID L. DUDEN AND EDWIN S. TEAL, OF CENTERTOWN, MISSOURI.

COMBINED WIRE STRETCHING AND SPLICING APPARATUS.

Application filed May 4, 1923. Serial No. 636,662.

To all whom it may concern:

Be it known that we, DAVID L. DUDEN and EDWIN S. TEAL, citizens of the United States, and residents of Centertown, in the county of Cole and State of Missouri, have invented a new and Improved Combined Wire Stretching and Splicing Apparatus, of which the following is a full, clear, and exact description.

10 This invention relates to improvements in wire stretching and splicing apparatus and has for one of its objects to provide a simple and effective apparatus by means of which two lengths of wire may be stretched to 15 and maintained at a desired tension and the meeting ends then brought together and spliced.

The above and other objects will appear more clearly from the following detail description, when taken in connection with 20 the accompanying drawing, which illustrates a preferred embodiment of the inventive idea.

In the drawing—

25 Figure 1 is a fragmentary side elevation of the apparatus, partly broken away and shown in section;

Figure 1^a is a side elevation of one of the 30 wire clamping devices employed in connection with the invention;

Figure 2 is a section on the line 2—2 of Figure 1; and

Figure 3 is a side elevation of the splicing head, forming a part of the invention.

35 Referring more particularly to the accompanying drawing, the numeral 5 indicates a sleeve member through which extends a shaft or rod 6 rotatable and movable in said sleeve member and provided adjacent one end thereof with an enlarged portion having ratchet teeth 8 which co-operate with similar teeth 9 formed upon the adjacent end of the sleeve member 5 for a purpose which will appear in the course 40 of the description. The shaft 6 is also enlarged at the extremity adjacent the portion 7 to provide a splicing head 10 having oppositely disposed openings 11 therein which are arranged diagonally in the head and

45 converge at the outer end thereof so as to receive the extremities 12 of two lengths of wire which are to be stretched and spliced.

50 Intermediate the ends of the sleeve member 5 the same is provided with a laterally extending pin 13 about which the inter-

mediate portion of a flexible element, such as a rope 14, is adapted to be looped. The rope is then wound about the sleeve member and the extremities 15 thereof then extended 60 in opposite directions. Each extremity 15 has fixed thereto a suitable wire clamping device 16 which may be of any desired construction and which is adapted to be attached to one of the wires to be stretched 65 at a suitable distance from the extremity 12 thereof. To stretch the two lengths of wire preparatory to splicing the extremities or meeting ends together, the apparatus includes a handle 17 slidably mounted upon the end of the shaft 6 remote from the head 10 and provided with oppositely disposed lugs 18 for engaging in notches 19 formed in the adjacent end of the sleeve member 5. The handle 17 is yieldably maintained in 70 interengagement with the sleeve member 5 by means of a coil spring 20 interposed between the handle 17 and a second handle 21 mounted upon a squared portion 22 of the shaft 6 and retained in engagement 75 thereon by a nut 23. After the wire clamps 16 have been attached to the wires to be stretched and the rope 14 has been properly coiled about the sleeve member 5, as shown in Figure 1, a rotation of the handle 17 in 80 the direction indicated by the upper arrow in said figure will wind the extremities 15 of the rope 14 upon the sleeve member 5, thus drawing the adjacent ends of the wires together, thereby stretching the same. In 85 thus stretching the wires the entire device is rotated bodily until the desired tension is attained.

To splice the extremities 12 of the wires while the tension thereon is being maintained, said extremities are each introduced into one of the openings 11 of the splicing head. The handle 21 is then rotated in the direction indicated by the lower arrow in Figure 1 to revolve the shaft 6 and, consequently, the splicing head 10 to twist or splice the extremities 12, as indicated at 24, at the same time stretching the wires between the points to which the clamping devices 16 are attached. The rotation of the shaft 6 is now relative to the sleeve member 5 and in revolving the ratchet teeth 8 of the portion 7 will move freely over the teeth 9, but will be held in yielding engagement therewith by the coil spring 20 which exerts an outward pressure upon the handle 21. However, the teeth 8 and 9 will prevent a

movement of the shaft in an opposite direction, thus permitting the operator to readily manipulate the handle 21 when forming the splice.

- 5 After the wires have been stretched and spliced and it is desired to detach the apparatus therefrom, it is desirable that the tension under which the rope 14 has been placed by the stretching action be relieved so as to 10 permit the clamps 16 to be detached from the wires. This is accomplished by moving the handle 17 longitudinally of the shaft 6 and toward the handle 21 against the tension of the spring 20 so as to disengage the 15 lugs 18 from the notches 19. When this is done the tension on the rope 14 is relieved and the sleeve member 5 will be free to rotate in an opposite direction from that indicated by the upper arrow in Figure 1 and 20 relative to the shaft 6 to loosen the coils of the rope extending thereabout. The splicing head 10 may then be withdrawn from engagement with the extremities 12 of the wires and the lugs 18 reengaged with the 25 notches 19 preparatory to another operation of the device.

What is claimed is:

1. In a wire stretcher and splicer, a sleeve member, a flexible element coiled about said 30 sleeve member and having its extremities adapted for connection to wires to be spliced, a shaft mounted in said sleeve member and rotatable therein in one direction

only, a splicing head formed upon said shaft and to which the extremities of said wires are connected, an operating handle for said sleeve for rotating the same to wind said flexible element thereon whereby said wires are stretched, and a second operating handle carried by said shaft for rotating the same in said sleeve member to splice the extremities of the wires which are stretched by the rotation of said sleeve member.

2. In a wire stretcher and splicer, a sleeve member, a flexible element coiled about said sleeve member and having its extremities adapted for connection to wires to be spliced, a shaft mounted in said sleeve member and rotatable therein in one direction only, a splicing head formed upon said shaft and to which the extremities of said wires are connected, an operating handle for said sleeve for rotating the same to wind said flexible element thereon whereby said wires are stretched, a second operating handle carried by said shaft for rotating the same in said sleeve member to splice the extremities of the wires which are stretched by the rotation of said sleeve member, and means interposed between said handles for yieldably maintaining the first named handle in interengagement with said sleeve member.

DAVID L. DUDEN.
EDWIN S. TEAL.
